UNITED STATES PATENT OFFICE.

VIRGINIUS J. MAYO, OF ERIE, PENNSYLVANIA, ASSIGNOR TO GEORGE H. NOBLE, OF SAME PLACE.

SEWING-MACHINE SHUTTLE.

SPECIFICATION forming part of Letters Patent No. 331,314, dated December 1, 1885.

Application filed November 28, 1884. Serial No. 149,033. (No model.)

To all whom it may concern:

Be it known that I, VIRGINIUS J. MAYO, a citizen of the United States, residing at Erie, in the county of Erie and State of Pennsylvania, have invented certain new and useful Improvements in Sewing-Machine Shuttles; and I do hereby declare the following to be a full, clear, and exact description of the invention, such as will enable others skilled in the art to which it appertains to make and use the same.

This invention relates to the construction of sewing-machine shuttles, and has for its objects improvements on the means for inserting the thread and applying the tension.

My device is illustrated in the accompanying drawings, as follows:

Figure 1 is a perspective view of one of my improved shuttles with the thread in place ready for use. Fig. 2 is a similar view showing the tension bar or clamp unclasped and open. Fig. 3 is a perspective view from the rear of the shuttle, and shows the parts in the same position as in Fig. 1. Fig. 4 is a similar view to that in Fig. 3 of an open-ended shuttle. Fig. 5 is a top or plan view of the shuttle-body seen in Fig. 4, the tension-bar being removed.

The letter A marks the shuttle-body; B, the tension-bar; C, the bobbin; D, the thread; $a\ a'$, the thread-slot in the shuttle-body. b is the forward attachment and pivot of the tension-bar. b' is the rave on the side of the tension-bar. b^2 marks the space between the points 1 and 2 on the tension-bar, which is the bearing-point of the tension-bar upon the thread. b^3 is a raised or arched part of the bar B, which forms a free threadway. b^4 is the cover of the end of the shuttle, and is part of or formed on the tension-bar. b^5 is the clinch or fastening of the tension-bar on the open-ended shuttle.

The essential features of my invention are the same in the two different constructions shown. In the construction shown in the first three figures the tension-bar is pivoted at one end at b , and at the other end it has an enlargement, b^4 , for closing the end of the shuttle. In the other construction shown the tension-bar is fixed at b by a screw and at b^5 by

clinching over the end of the body. In this construction the slot $a\ a'$ is deflected from the points 3 to 4, so as to pass out at one side of the bar. A deflection of the bar would serve the same purpose as the deflected slot.

In the construction shown in first three figures the slot does not need to end at one side of the bar, and hence it is not deflected, but it could as well be so, if desired, without in any way affecting the operation of the shuttle.

It is not new to form the tension-bar with an end cover thereon and pivot the same, as shown, nor is it new to secure the tension-bar at each end and leave the shuttle open, and therefore these features form no part of my invention.

The thread-slot in the body of the shuttle consists of the slots $a\ a'$ and $a'\ a^2$, which lie at an acute angle to each other and intersect at the point a' , near the inner end of the bobbin-chamber. In other words, the thread-slot extends from the back end of the shuttle to near the inner end of the bobbin-chamber, and then deflects back at a sharp angle to the point a^2 .

To insert the thread, all that is required is to draw it along the slot $a\ a'$ to the point a' , and then back in the branch slot $a'\ a^2$ to the point a^2 . This may be done when the tension-bar is in place over the slot or not, as the case may be. The tension-bar B is so formed that the space b^2 , from 1 to 2, presses upon the shuttle-body sufficiently to give the proper tension to the thread which passes under it from the point a^2 to the point 2 on the tension-bar. Rearward from the point 2 the tension-bar is arched up, forming the raised part b^3 , under which the thread has free passage as the shuttle moves to and fro. It should be observed that the draft of the thread from the tension-space is direct, and not back over an edge or through an eye, as is common. This is a great advantage, as it greatly lessens the liability of breaking the thread, and is one of the essential features of my invention. It will be seen that this result is effected by the arrangement of the point or eye a^2 , the bearing-space b^2 , and the free or arched space b^3 , in a line in the order named with the line of forward motion of the shuttle.

The operation of my device will be suffi-

ciently understood from the foregoing description.

What I claim as new is—

1. In a sewing-machine shuttle, the combination, substantially as herein set forth, of a shuttle-shell provided with a thread-slot which extends from the rear end of the shuttle-body to the forward end of the bobbin-chamber, and then offsets back toward the rear end, and a tension-bar covering said slot, which presses upon the shuttle-body back of the offset of said slot.

2. In a sewing-machine shuttle, the combination, substantially as herein set forth, of a shuttle-shell having the thread-slot $aa'a'$, and the tension-bar B, covering said slot and having its bearing b^2 back of the end a^2 of said slot.

3. In a sewing-machine shuttle, the combination, substantially as herein set forth, of a shuttle-shell having a thread-slot which extends from the rear end of the shuttle body to the fore part of the bobbin-chamber, and then offsets back toward the rear end, and a tension-bar which has its bearing-space back of the end of said offset, and a raised part for giving a free thread-space back of said bearing-space.

4. In a sewing-machine shuttle, the combination, substantially as herein set forth, of a shuttle-shell having the thread-slot $aa'a'$, and the tension-bar B, covering said slot, and having the bearing-space b^2 back of the end a^2 of said slot and the raised space b^3 back of said bearing-space.

5. In a sewing-machine shuttle, the combination, substantially as herein set forth, of the tension-bar B, having bearing-space b^2 and raised space b^3 , and both of its ends secured to the shuttle-body, and a shuttle-shell having a thread-slot, which begins at the rear end of the shuttle-body at one side of the tension-bar and passes under the tension-bar and forward to near the inner end of the bobbin-chamber, and then offsets backward and ends at the forward end of the bearing-space b^2 of the tension-bar.

In testimony whereof I affix my signature in presence of two witnesses.

VIRGINIUS J. MAYO.
